UNITED STATES PATENT OFFICE.

WILLIAM F. WARNER, JR., OF ROCHESTER, NEW YORK, ASSIGNOR TO HENRY CONNOLLY COMPANY, INC., OF ROCHESTER, NEW YORK, A CORPORATION OF NEW YORK.

LOOSE-LEAF BINDER.

Application filed November 29, 1926. Serial No. 151,282.

The present invention relates to loose leaf binders and more particularly to the type designed for holding the leaves in overlapping relation so that an edge of one sheet projects beyond an edge of the other in order that the projecting edges may be used as an index. An object of this invention is to provide a novel arrangement of posts or impaling projections upon one of the binding members and a transfer member which is incorporated in the binder so that exceptionally short sheets may be employed in the binder while, at the same time, making provision for shifting, through the transfer member, of sheets on the binding member relatively to other sheets.

To this and other ends, the invention consists of certain parts and combinations of parts, all of which will be hereinafter described: the novel features being pointed out in the appended claims.

In the drawings:

Fig. 1 is a perspective view of one embodiment of the invention;

Fig. 2 is a fragmentary perspective view of one of the binding members and the transfer member;

Fig. 3 is a transverse section through the binder adjacent the binding member;

Fig. 4 is a longitudinal section through another embodiment of the binder;

Fig. 5 is a perspective view of this other embodiment of the invention; and

Fig. 6 is a transverse section through the embodiment illustrated in Fig. 5 adjacent the binding members.

In the embodiment of the invention illustrated in Figs. 1 to 4, 1 and 2 indicate the binding members. Covers 3 are hinged to these binding members at 4 and a back piece 5 hingedly connects the binding members. Projecting from the binding member 1 are a number of posts or impaling projections 6. These posts are arranged in groups of two each except for the end posts, the groups being spaced apart a greater distance than the distance between the members of the groups. At least some of these posts may be extended beyond the others and provided with shoulders 7 for entry into openings 8 in the casing of the binding member 2 in order to be engaged by a locking means in the form of a sliding bar 9 mounted in the binding member 2 and pressed toward locking position by a spring 10, one end of the locking

member being provided with a finger piece 11 through which the locking member 9 may be moved out of engagement with the shoulders 7.

Associated with the binder is a transfer member 13 in the form of a plate provided with posts or impaling projections 14. These posts in this embodiment are equidistantly spaced at a greater distance apart than the distance between the groups on the binding member 1. The plate portion of this transfer member may be provided with a number of groups of openings 15, the number of such groups corresponding with the number of posts provided with shoulders 7 so that the long posts or impaling projections may pass through said openings in order to pass into the openings 8 of the binding member 2 for engagement by the locking member. This transfer member may also be provided with shouldered projections 16 which are adapted to pass into openings 17 of the binding member 2 in order to be engaged by the locking member 9.

The leaves 18 of this embodiment are each considerably shorter than the length of the binding members so that they may lie in overlapping relation with the edge of one projection over the edge of the other so that the projecting portions may be utilized as an index for the matter contained on the leaves. Each leaf has a plurality of openings 19 in one margin thereof, these openings being equidistantly spaced. In this embodiment the distance between these spaces is equal to the distance between the members of the groups so that when a leaf fits upon a group the members of each group pass through a number of openings without any openings between them. The distance, however, is such that the posts or projections 14 on the transfer member 13 may occupy a plurality of positions in openings between each group on the binding member 1, thus permitting the posts or projections on the transfer member to be fitted in any of the openings in the leaf between the groups on the binding member 1 for the purpose of permitting any number of leaves to be shifted to the transfer member and off the posts or projections on the binding member 1, and, thereafter, the transfer member, with such leaves, to be shifted to another position between the groups or posts on the binding member 1 in order that the position of the leaves carried by the transfer member

may be shifted relatively to the leaves carried by the binding member 1. The openings 15 in the transfer member also permit this action. In this embodiment three openings are 5 provided in the transfer member and between each group of posts three openings are unoccupied by the posts of the binding member 1 in the leaves, so that in the normal position of the posts with the shoulders 7 in the central 10 opening of each group 15, the transfer member may be shifted between the groups of posts on the binding member 1 either toward the top or bottom of the binder.

In the embodiment of the invention shown 15 in Figs. 5 and 6, one of the covers 3^a is hinged to the binding member 1^a, while the other cover 3^a is hinged to the transfer member 13^a. The binding member 2^a connects with the binding member 1^a by a back piece 5^a hinged 20 to both binding members. In this embodiment, the impaling posts or projections 6^a are also arranged in groups, but the number of groups is fewer than that of the embodiment shown in Fig. 1, while the distance between 25 the members of the groups is greater. The transfer member 13^a has its impaling projections 14^a also arranged in groups, the distance between the members of the groups on the transfer member and the members of the 30 groups on the binding members, however, being the same. The leaves 18 are, like the embodiment shown in Fig. 1, formed with a marginal series of equidistantly spaced openings 19. The distance between these openings is 35 less than the distance between the posts on the binding member 1^a and the transfer member 13^a so that when a leaf fits on a group of posts, there will be provided between each post of a group an opening 19^a. The distance between the groups of posts on the binding member 1^a is such that the group of posts on the transfer member 13^a may occupy a 40 plurality of positions between the posts on the binding member 1^a. In this instance, five leaf openings are placed between each group of posts on the binding member 1^a and, as only two posts are provided in each group on the transfer member 13^a, it is possible to shift the transfer member to a plurality of positions 45 between the posts of the binding member 1^a in order to shift the leaves toward the top or the bottom of the binding member 1^a through the means of the transfer member 13^a as before pointed out. At least some of the 50 posts 6^a are longer than the others and are provided with shoulders 7^a adapted to pass through openings 15^a in the transfer member in order to engage in the locking device 9 on the binding member 2^a. The transfer member 13^a also has shouldered projections 16 for engagement with the locking device 9 as in the other embodiment.

In both embodiments of the invention, by arranging the posts or impaling projections 55 in groups which are separated only a short

distance, it is possible to hold in the binder leaves which are short in length as each leaf will then be engaged by more than one post. The embodiment shown in Fig. 5 permits the holding of a leaf of much smaller length than the embodiment shown in Fig. 1, as the number of posts of this embodiment is much greater than the embodiment shown in Fig. 5 the distance between the posts is less, and the distance between the group of posts is less. 75

What I claim as my invention and desire to secure by Letters Patent is:

1. A loose leaf binder comprising two binding members, one provided with a locking device and the other having a plurality of impaling projections arranged in groups, at least two of said projections having shoulders thereon for engagement with the locking means of the first mentioned binding member, leaves of less length than the binding members, each provided with a plurality of equidistantly spaced openings along one margin adapted to fit on the impaling projections in overlapping relation so that one may project beyond the other, and a transfer member having impaling projections arranged to lie between the groups of impaling projections on the second mentioned binding member, the distance between the groups on the binding member being greater than the distance between adjacent members in any one group and being such that the impaling projections on the transfer member, while lying in openings of the leaves, may be moved to occupy a plurality of positions. 100

2. A loose leaf binder comprising two binding members, one provided with a locking device and the other having a plurality of impaling projections arranged in groups, at least two of the projections having shoulders thereon for engagement with the locking means of the first mentioned binding members, leaves of less length than the binding members, each provided with a plurality of equidistantly spaced openings along one margin, the distance between the openings being equal to the distance between the impaling projections of the groups, and a transfer member having impaling projections arranged to lie between groups of impaling projections on the second mentioned binding member being such that the impaling projections on the transfer member may, while lying in openings of the leaves, occupy a plurality of positions. 110

3. A loose leaf binder comprising two binding members, one provided with a locking device and the other having a plurality of impaling projections arranged in groups, at least two of said projections having shoulders thereon for engagement with the locking means of the first mentioned binding member, leaves of less length than the binding member being provided with a plurality of equidistantly spaced openings along one margin. 125

gin, said openings being spaced apart a distance equal to the distance between the impaling projections of the groups, so that the leaves may fit on the impaling projections in an overlapping relation with one projecting beyond the other, and a transfer member having equidistantly spaced impaling projections, the

distance between the impaling projections of the transfer member being greater than the distance between the groups on the binding member and the distance between the groups on the binding member being such that the transfer member may while lying in openings in the leaves be moved to occupy a plurality of positions.

WILLIAM F. WARNER, JR.
